LABELING MACHINE

Derek Howard Fairest, Sheffield, England, assignor to Morgan Fairest Limited, Sheffield, England

Application February 27, 1951, Serial No. 212,933
In Great Britain March 14, 1950

5 Claims. (Cl. 216—55)

1

This invention relates to labelling machines of the type in which a label adhering by wet gum to one plate is transferred by a suction pusher to one of a number of delivery plates to which it is then held, gummed side out, by suction openings in the plate for application to the article to be labelled, the delivery plates moving in turn from transfer position to application position in turn. With the delivery plates forming the sides of an intermittently rotatable "box," each time the box comes to rest a label is transferred to one of the sides as a label is applied by another side to one of a series of articles fed in synchronism with the rotatory movements, and a high rate of label application is achieved, with each label placed precisely on a delivery plate because of the suction control exercised by the transfer pusher. The suction has to be interrupted at the transfer pusher to allow the label to adhere to the delivery plate by the suction there applied to the non-gummed side of the label, i. e., the side bearing the printed matter, and in the construction of machine described in U. S. Patent No. 2,509,902 of S. E. Banks the suction at the delivery plates has been interrupted on the application of each label to the article and during the idle movement of the plates to the position at which further labels are transferred to them. The necessarily complicated rotary valve-gear has to be finely adjusted and is in danger of becoming blocked by paper-dust removed from the rough back of the label by the pusher and drawn into the mechanism, with ultimate reduction of the degree of suction to below what is effective to control the labels.

One object of the present invention is to simplify the valve mechanism, with consequent avoidance of fine adjustment. A further object is to prevent paper-dust from being drawn into the valve mechanism.

According to the present invention, a labelling machine of the type having a rotatable delivery box with suction openings in its sides to hold labels transferred, gummed-side out, by a suction pusher movable towards and from a side of the box in one position of the box, the intermittent rotation of the box carrying the label to another position for application to the article to be labelled, comprises continuous connections from a source of suction to the openings in all the sides of the box, a suction connection to the pusher, a valve in the said connection to the pusher, and means operating intermittently in phase with the movements of the pusher and the box to open and close the valve for application

2

to the pusher of suction only during its movement towards the box.

The suction may be supplied from a source common to both the box and the pusher, e. g. by being applied to a chamber in communication with the openings in the side of the delivery plate, this chamber being sealed by a ring attached to a resilient bellows and pressed by a spring on to a corresponding seating ring, thus permitting the free rotation of the delivery box with adequate maintenance of suction in the chamber and allowing for the ready removal and replacement of the box, as may be necessary for interchange of the faces of its sides with openings in accordance with changes in the size or shape of the labels to be applied. Separate sources of suction may, however, be used for the box and the pusher, as may be desirable to avoid intake of air at either of these parts interfering with the degree of suction at the other part.

It is found that continuous suction to the openings on all sides of the delivery box permits sufficient holding suction at the faces where labels are being held, notwithstanding the small inflow of air through the openings in an idle face. By the resultant elimination of valves controlling the suction to the separate faces, removal and replacement of the delivery box merely calls for the breaking and remaking of the seal formed by the sealing ring.

In order to avoid having to evacuate the whole interior of the delivery box, the suction chamber may be kept small and connected by individual pipes to each face, where branch passages lead to as many fine openings as are necessary for the holding of a label. Interchange of faces with different arrangements of openings may then be effected without interference with the internal suction arrangement of the box.

The invention will now be described in greater detail with reference to the accompanying drawings, in which

Figure 1 is a part sectional elevation generally on the line 1—1 of Figure 2;

Figure 2 is a plan view; and

Figure 3 is a sectional detail of Figure 2.

In Figure 2, normal parts of the machine that lie above the plane of that figure are shown in chain-dotted line, to leave the mechanism according to the invention clearly exposed.

A label 10 having been brought from a feed-stack to the position shown by the normal operation of the machine, a pusher 11 is movable towards the one face 12A of an intermittently rotated delivery box 13 that happens to be fac-

ing the pusher. The pusher, now at 11A, presses the label as at 10A to the face 12A, and the label is transferred to the face 12A, and the pusher recedes, leaving the label adhering to the face 12A, as is explained below. Two stages of rotation of the box 13 bring the face 12A to the position 12B, where the label held to the face is secured to a bottle 14, which is being rolled along a guide wall 15. The pusher 11 contacts a small ungummed portion of the side of the label 10 facing away from the face 12A, so that the box 13 carries the label gummed-side out, for that side to be presented to the bottle 14.

The box 13 is removably secured by a wing nut 16 to a driving shaft 17. A sealing ring 18 is pressed by a spring 19 round a bellows 19A on to a stationary seating ring 20 below the box, within which is a small suction chamber 21. An annular passage 22 provides a communication to flexible tubes 23, one for each face of the box 13, communicating through an aperture 24 in the permanent side 25 of the box, and thence by passages 26 to any desired suction openings 27 as may be required for the particular size and shape of label in use. The passages 26 and openings 27 are in a detachable side 28 of the box, permitting use of the box for different sizes and shapes of label.

Suction from a main supply connection 29 is applied to the chamber 21 by a tube 30, so that suction is continuous to the four faces of the box 13. In general, there will be at least two labels adhering to faces of the box, e. g. one just applied by the pusher 11 and one in transit to the face position 12B, and possibly a third label awaiting transfer to the bottle 14, so that only one or two faces do not have the openings 27 covered by a label. The small admission of air thus permitted does not interfere with the holding power of the suction at the faces bearing labels, provided a sufficient degree of suction is applied from the supply connection 29.

A valve box 32 surrounds the shaft 17 below the box 13, and contains a valve bobbin 33 pushed towards a rotary cam 34 on a shaft 35 by a spring 36. A port 37 connects the chamber 21 to an annulus 38 in the bobbin 33 when the bobbin is pushed to the right (Figure 3) by the cam 34, and admits suction to a flexible tube 39 through a filter 40 and flexible tube 41 to the suction passage 42 of the pusher 11. When the bobbin 33 is retracted, the annulus 38 is cut off from the port 37, and exhausts itself at 43.

The cam 34 causes suction to be applied to the pusher 11 for the latter to hold a label 10 as it transfers it to the box 13, and cuts off suction as the label approaches the face 12A, to allow the continuously applied suction at that face to take over the label, the label remaining accurately positioned during transfer by the pusher suction and being held correctly positioned by the box suction during its movement to the bottle 14.

Any paper-dust removed from the back of the label at the pusher is caught in the filter 40, and

so is not liable to clog the valve box 32. But in any case, the simple valve mechanism in the box 32 is wide-ported, and itself is not such as to be readily clogged. Adjustment of timing is readily effected, externally of the valve box, by adjustment or replacement of the cam 34.

What I claim is:

1. A labelling machine of the type having a rotatable delivery box with suction openings in its sides to hold labels transferred, gummed-side out, by a suction pusher movable towards and from a side of the box in one position of the box, the intermittent rotation of the box carrying the label to another position for application to the article to be labelled, said machine comprises continuous connections from a source of suction to the openings in all the sides of the box, a suction connection to the pusher, a valve in the said connection to the pusher, and means operating intermittently in phase with the movements of the pusher and the box to open and close the valve for application to the pusher of suction only during its movement towards the box.

2. A labelling machine as in claim 1, wherein the box and pusher connections are supplied from a common source of suction.

3. A labelling machine of the type having a rotatable delivery box with suction openings in its sides to hold labels transferred, gummed-side out, by a suction pusher movable towards and from a side of the box in one position of the box, the intermittent rotation of the box carrying the label to another position for application to the article to be labelled, said machine comprising a suction chamber below the box, a connection from a source of suction to the chamber, continuous connections from the chamber to the openings in all the sides of the box, a valve, a port from the chamber to the valve, a suction connection from the valve to the pusher, means operating intermittently in phase with the movements of the pusher and the box to open and close the valve for application to the pusher of suction only during its movement towards the box and sealing ring, a resilient bellows, a spring, and a seating ring co-operating to permit rotation of the box while sealing the chamber.

4. A labelling machine as in claim 3, comprising individual pipes making the continuous connection from the suction chamber to the sides of the box.

5. A labelling machine as in claim 3, comprising a filter disposed in the connection between the valve and the pusher.

DEREK HOWARD FAIREST.
